UNITED STATES PATENT OFFICE.

BAYARD GUTHRIE, OF PITTSBURGH, AND JOSEPH P. KARCH, OF SEWICKLEY, PENNSYLVANIA, ASSIGNEES TO C. P. CARPENTER, TRUSTEE, OF PITTSBURGH, PENNSYLVANIA.

ELECTRIC FURNACE.

1,086,102.

Specification of Letters Patent.

Patented Feb. 3, 1914.

Application filed June 29, 1912. Serial No. 706,596.

To all whom it may concern:

Be it known that we, BAYARD GUTHRIE, of Pittsburgh, and JOSEPH P. KARCH, of Sewickley, in the county of Allegheny and 5 State of Pennsylvania, citizens of the United States, have invented a new and useful Improvement in Electric Furnaces; and we do hereby declare the following to be a full, clear, and exact description thereof.

10 This invention relates to the melting of metals by heat produced by an electric arc in combination with a resistance, and is particularly concerned with improved apparatus for this purpose.

15 The invention constitutes an improvement over that described in Letters Patent of the United States No. 979,663, more particularly with a view to producing an apparatus better suited for operation with a direct current or single phase alternating current where quarter phase current is not available.

The invention has further for its object to provide improved means for mounting a 20 mold in constant relation to the outlet of the crucible of the furnace whereby the metal discharged from the said outlet will flow directly to the center of the bottom of said mold without in its passage contacting 25 with the sides of the mold.

In the accompanying drawings Figure 1 is a plan view in partial horizontal section of an apparatus embodying our invention. Fig. 2 is a vertical section showing the mold 30 and the support in elevation. Fig. 3 is a sectional view at right angles to that shown in Fig. 2. Fig. 4 is a horizontal sectional view. Fig. 5 is a sectional view on the line 5-5 Fig. 3. Fig. 6 is a detail of the steady 35 plates for the carrying bars of one of the electrodes; and Fig. 7 is a rear view of one of the electrodes showing the connected terminal for the electric circuit in conjunction therewith.

40 In the embodiment of our invention herein selected for illustration, 1 indicates the furnace casing which may be provided with a bottom plate 2 pivotally secured thereto and a removable cover plate 3 having an opening 4 to afford access to the crucible 5 that opening being provided with a movable cover 6. The casing may be and pref-

erably is of substantially cylindrical section and is preferably cast either with the lugs or trunnion bases 7, 7 to which cylindrical 55 trunnions 8, 8 may be secured. These trunnions 8 may be mounted in suitable standards or brackets such as illustrated in Patent No. 979,663, above referred to and any desired means, for tilting the furnace such, for example as that illustrated in said patent, may be provided. The crucible 5 which may be of suitable refractory composition, such for example as plumbago, 60 clay and sand, is supported within the casing by one or more layers 9 of fire brick or other refractory material whereby it is thoroughly insulated from the bottom plate of the casing and is surrounded by a wall 10 of fire brick extending practically to the top 70 of the casing, but so arranged as to leave between itself and the crucible a chamber or pair of chambers 11 separated from each other by refractory partitions 12-12, Figs. 1 and 4. These partitions at their inner 75 edges conform closely to and fit snugly against the side of the crucible. Within the lateral chambers 11, 11 are mounted the electrodes 13, 13, which as here shown are in the form of substantially semi-conical body 80 portions of reduced diameter at the bottom to fit snugly against the lower portion of the crucible wall and flaring at the top to provide spaces 14, 14 around the crucible which may be filled with broken carbon for the 85 purpose of furnishing resistance to break up and make a more even distribution of the electric arc over the surface of the crucible. This carbon may be fed into the space 90 through suitable holes 3' in the cover plate 3. Each of the carbon electrodes 13 is provided preferably with a fastening lug or stem 13' 95 preferably bolted into the copper electrode holders 15, 15, which in turn are provided with the portions 15^a having terminal sockets 15^b for the usual connection with the terminals of the cables carrying the current. The electrode holders 15 are carried by suitable carrying bars 16 bolted to and manipulated from said holders, these carrying 100 bars passing through slots 17, 17 (Fig. 6) of a steady plate or disk 18 of circular form to fit within the hollow trunnions 8. These steady plates are each provided with oppo-

site lugs 19 tapped for set screws 20 by which each plate is fixed in position within its trunnion end said plates are also provided with lugs 21 preferably on the diameter at right angles to the lugs 19 by which each steady plate or disk is held against rotation or rocking upon its set screws 20. Each plate is also provided with a central opening 22 through which the cables carrying the current may pass to the electrodes. The outer ends of the trunnions are closed by cover plates 23 (Fig. 5) slotted as at 24, 24 to pass the electrode carrying bars 16 and with apertures 25 past the current cable. 15 The carrying bars are united at their outer ends by a yoke 26 (Figs. 1 and 3) having swiveled therein a screw member 27 threaded into the cover plate 23 and having an angle end or head 28 by which the screw 20 may be turned to adjust the position of the electrode held by the carrying bars. By this means the electrode may be adjusted to the proper position to receive and firmly hold the crucible at the bottom as shown 25 in Fig. 3.

By reason of the contacting of the lower edges of the electrodes with the bottom of the crucible and the divergence of the electrodes upwardly away from the crucible, 30 the heating effects due to the arcing across of the electrodes to the crucible is more intense at the top than at the bottom and gradually reduces the intensity as the bottom is reached. Thus the molten metal at 35 the top of the crucible trickles down through the unmelted mass at the bottom of the crucible whereby it maintains the proper heat of the molten mass. The broken carbon interposed between the crucible and the electrodes serves to break up the arcing effect 40 and distribute it more evenly over the surface of the crucible, and this prevents undue eating away of the crucible at any particular point or points. The portion of the fire brick 9 introduced at the ends of the electrodes prevents arcing across from one electrode to the other and necessitates the passage of the arc to and through the crucible 45 of the electrode thereby utilizing the full effect of the current for the reduction process. In this form of apparatus, moreover, but two electrodes are employed directed to opposite points of the crucible, thereby rendering the device particularly adapted for operation 50 with direct current or single phase alternating current. The furnace is provided with a suitable spout 29 having a flared inner end 30 adapted to fit closely about the upper edge of the crucible and having a lip 31 to 55 insure the directing of the molten contents of the crucible into the spout. The spout projects some distance beyond the outer periphery of the wall and is provided with a pair of hooks 32 adapted to engage links 33

threaded at their lower ends into lugs 34 of 60 the holding ring 35 within which the mold 33 is held, said mold having lugs 37 adapted to rest upon the upper edge of said holding rings. The hooks 32 are so positioned relatively to the outer end of the spout that the spent will invariably discharge the contents of the crucible directly to the center of the bottom of the mold and without permitting it to contact in its passage down into the mold with the side walls thereof thereby a 70 faultless ingot may be produced in the mold.

It will be seen in the above description as well as in Patent No. 973,663, the crucible and pouring is held by means of the electrodes partially through the agency of the 75 broken carbon interposed between the electrodes and the crucible. The crucible is also situated in position by the lowest portions of the fire brick lining which extends between the ends of the electrodes and by 80 means of the spout engaging with the upper edge of the crucible.

While we have herein described a particular embodiment of our invention, it is to be understood that the same may be altered 90 in details, and in arrangements of parts within the scope of the appended claims.

We claim—

1. An electric furnace comprising a crucible, a pair of electrodes each of a shape 95 and so located as to inclose substantially one-half of said crucible and means for adjusting said electrodes toward and from the crucible.

2. An electric furnace comprising a crucible, a pair of electrodes of a shape and so located as to almost completely encircle the crucible and means for adjusting said electrodes relatively to said crucible.

3. An electric furnace comprising a crucible, a pair of electrodes each inclosing a comparatively large area of the crucible, said electrodes each contacting with the crucible at the bottom thereof and diverging toward the top to increase the heating effect 105 of the electric arc from the bottom to the top of the crucible.

4. An electric furnace comprising a crucible, a pair of electrodes each inclosing substantially one-half of the crucible, means for 115 preventing direct arcing from one of the electrodes to the other, said electrodes being shaped to increase the electric heating effect from the bottom to the top of the crucible.

5. An electric furnace comprising a crucible, a pair of electrodes arranged upon opposite sides thereof, means to adjust said electrodes toward and from said crucible, a broken carbon resistance between said electrodes and said crucible, the upper portions 125 of said electrodes being farther removed from the crucible than the lower portions.

6. In an electric furnace, a casing having

- 1 a refractory and non-conducting lining, a
2 crucible mounted within said lining, said
3 lining having portions contacting with op-
4 posite sides of said crucible forming cham-
5 bers upon opposite sides of the crucible sep-
6 arated from each other by said lining, elec-
7 trodes within said chambers separated from
8 each other by said lining and adapted to be
9 adjusted toward and from said crucible.

10 7. In an electric furnace, a casing having
11 a refractory and non-conducting lining, a
12 crucible mounted within said lining, said
13 lining having portions contacting with op-
14 posite sides of said crucible forming cham-
15 bers upon opposite sides of the crucible, elec-
16 trodes within said chambers separated from
17 each other by said lining, the lower por-
18 tions of said electrodes contacting with said
19 crucible and the upper portions diverging
20 therefrom to increase the heating effect on
21 said crucible from the bottom to the top.

22 8. In an electric furnace, a casing having
23 a refractory and non-conducting lining, a
24 crucible mounted within said lining, said
25 lining having portions contacting with op-
26 posite sides of said crucible forming cham-
27 bers upon opposite sides of the crucible, elec-
28 trodes within said chambers separated from
29 each other by said lining, the lower portions
30 of said electrodes contacting with said cruci-
31 ble, and the upper portions diverging
32 therefrom to increase the heating effect on
33 said crucible from the bottom to the top,
34 and a resistance element interposed between
35 said electrodes and said crucible.

36 9. In an electric furnace, a crucible, a pair
37 of electrodes adjacent thereto, a bridge wall
38 of refractory non-conducting material sep-
39 arating said electrodes so that the heat gen-
40 erated may be deflected to or concentrated
41 in said crucible.

42 10. In an electric furnace, the combina-
43 tion of a tiltable casing having a lining of
44 fire-brick, said lining having a dividing wall
45 forming chambers upon opposite sides of
46 said crucible, opposite electrodes in said
47 chambers inclosing comparatively large
48 areas of said crucible, means for adjusting
49 said electrodes whereby they may be in con-
50 tact with said crucible and position the same
51 within said furnace.

52 11. In an electric furnace, the combina-
53 tion with a tiltable casing having a lining of
54 fire-brick forming a division wall in the
55 furnace, opposite electrodes adjacent said
56 crucible and adapted in conjunction with
57 said division wall to hold and support said
58 crucible when pouring.

59 12. In an electric furnace, the combina-
60 tion with a tiltable casing, of a refractory
61 lining therefor, a crucible inclosed within
62 said lining, said lining having a dividing
63 wall forming chambers upon opposite sides
64 of said crucible, electrodes in said opposite

65 chambers shaped to contact with the lower
66 portion of said crucible and diverging from
67 the upper portion thereof, a resistance ele-
68 ment interposed between said electrodes and
69 said crucible, said division wall being adapt-
70 ed to hold and support said crucible when
71 pouring.

72 13. In an electric furnace, the combina-
73 tion with a tiltable casing, of a refractory
74 lining therefor, a crucible inclosed within
75 said lining, said lining having a dividing
76 wall forming chambers upon opposite sides
77 of said crucible, electrodes in said opposite
78 chambers shaped to contact with the lower
79 portion of said crucible and diverging from
80 the upper portion thereof, a resistance ele-
81 ment interposed between said electrodes and
82 said crucible, a spout leading from said
83 crucible to the exterior of said furnace, said
84 division wall being adapted to hold and sup-
85 port said crucible when pouring.

86 14. In an electric furnace, the combina-
87 tion with a tiltable casing, of a refractory
88 lining therefor, a crucible inclosed within
89 said lining, said lining having a dividing
90 wall forming chambers upon opposite sides
91 of said crucible, electrodes in said opposite
92 chambers shaped to contact with the lower
93 portion of said crucible and diverging from
94 the upper portion thereof, a resistance ele-
95 ment interposed between said electrodes and
96 said crucible, a spout leading from said cruci-
97 ble to the exterior of said furnace, said
98 division wall being adapted to hold and sup-
99 port said crucible when pouring, a mold
100 supported on said furnace in constant defi-
101 nite relation to the outer end of said spout.

102 15. In an electric furnace, the combina-
103 tion with a tiltable casing, of a refractory
104 lining therefor, a crucible inclosed within
105 said lining, said lining having a dividing
106 wall forming chambers upon opposite sides
107 of said crucible, electrodes in said opposite
108 chambers shaped to contact with the lower
109 portion of said crucible and diverging from
110 the upper portion thereof, a resistance ele-
111 ment interposed between said electrodes and
112 said crucible, a spout leading from said cruci-
113 ble to the exterior of said furnace, said
114 division wall being adapted to hold and sup-
115 port said crucible when pouring, a mold
116 swingingly supported on said furnace on an
117 axis passing through the end of said spout.

118 16. In an electric furnace, the combina-
119 tion with a tiltable casing, of a refractory
120 lining therefor, a crucible inclosed within
121 said lining, said lining having a dividing
122 wall forming chambers upon opposite sides
123 of said crucible, electrodes in said opposite
124 chambers shaped to contact with the lower
125 portion of said crucible and diverging from
126 the upper portion thereof, a resistance ele-
127 ment interposed between said electrodes and
128 said crucible, a spout leading from said

crucible to the exterior of said furnace, said division wall being adapted to hold and support said crucible when pouring, a mold supported on said furnace on an axis so 5 relatively positioned with respect to the spout as to cause the metal discharged therefrom to be received directly at the center of the bottom of said mold.

In testimony whereof, we the said BAYARD GUTHRIE and Joseph P. Karch have to hereunto set our hands.

BAYARD GUTHRIE,
JOSEPH P. KARCH.
